GEORGE R. WELCH, OF DETROIT, MICHIGAN

INTAKE MANIFOLD FOR INTERNAL COMBUSTION ENGINES

Application filed July 22, 1929. Serial No. 380,131.

The invention relates to intake manifolds for internal combustion engines of that type in which provision is made for the heating of the mixture when the engine is operating under certain conditions, such for instance as in cold weather, and for cutting out or regulating the heat when operating under different conditions. It is the object of the present invention first to obtain 10 a simplified construction; further, to obtain an instantaneous response when adjustment is made and further, to obtain various advantages as hereinafter set forth.

In the drawings:

15 Figure 1 is a plan view partly in horizontal section showing a portion of the exhaust manifold and intake manifold of an internal combustion engine to which my improvement is applied;

20 Figure 2 is a similar view showing the parts in a different position of adjustment.

Figure 3 is a vertical cross section on line 3—3 of Figure 2.

As illustrated, A is an exhaust manifold 25 of an internal combustion engine and B is the intake manifold therefor which has a vertically extending portion B' and a horizontally extending portion B². Centrally within the exhaust manifold A is a chamber C preferably formed by an inward bending of a portion of the outer wall as indicated at D. The horizontal portion of the intake manifold B is also fashioned so as to have a portion opposite the central portion 30 of the exhaust manifold A and provided with an inwardly extending portion E which abuts against and forms a gas tight joint with the portion D. Within this portion E is a hollow member F centrally pivoted at G and adapted to be turned from a position as shown in Figure 1 where it forms a valve for a closing connection between the manifold B and the chamber C to a position at right angles thereto as shown in Figure 2. This hollow member F has an opening H on its lower side which in the position shown in Figure 2 registers with the vertical portion B' of the intake conduit, cutting off direct communication 40

45 between said portion and the horizontal portion

55 tion B² and deflecting the incoming mixture into the chamber C from which point it will divide and pass outward on opposite sides of the member F into the portion B². Thus whenever the parts are in the position shown in Figure 2, the carbureted mixture will be directed against the hot wall D of the chamber C to more perfectly vaporize and commingle the liquid fuel with the air. On the other hand, when the member F is turned 60 to the position shown in Figure 1, the mixture passes from the portion B' to the portion B² of the manifold without contact with any heated surface and the fact that the member F is hollow forms a heat insulation between the chamber C and the intake manifold.

65 One of the principal advantages of my improved construction over devices that have heretofore been used is that when the 70 engine is running the wall D is always heated by the exhaust gases so that whenever the member F is turned into the position shown in Figure 2 the heating of the mixture will occur instantaneously. This is 75 quite different in effect from the constructions where exhaust gases are deflected to surround a portion of the intake and which therefore require a time interval to heat up this portion before the mixture is heated. Another advantage is as before mentioned 80 that the hollow member F forms a heat insulation for preventing conduction of heat from the chamber C into the manifold B. A still further advantage is the simplicity 85 of the construction which is one that can be manufactured at low cost.

86 What I claim as my invention is:

1. The combination with an exhaust manifold of an internal combustion engine, of 90 an outwardly opening chamber within said manifold having its walls heated by the exhaust gases, an intake manifold having apertured laterally extending branch portions registering with the opening in said chamber, and a vertical portion connecting said branch portions and a hollow member rotatively mounted within said inlet manifold and in one position of adjustment cutting off 95 communication between the same and said 100

chamber, said member in another position of adjustment cutting off direct communication between said vertical portion and branch portions of said inlet and directing the incoming mixture first into said chamber and then outward into said branch portions.

2. In an internal combustion engine, the combination of an exhaust manifold having a wall thereof depressed inwardly to form an outwardly opening chamber within the manifold, an intake manifold having horizontal branch portions and a vertical portion connecting thereto, said branch portions being apertured in registration with the opening in said chamber and provided with a portion surrounding said aperture and connecting the said chamber, and a hollow member rotatively secured within said connection portion adapted in one position of adjustment to close said aperture and cut off communication between said inlet manifold and chamber and in another position of adjustment to direct the incoming gases from the vertical portion of said inlet conduit into said chamber and thence outward into the branch portions.

3. In an internal combustion engine, the combination of an exhaust manifold having a wall thereof depressed to form a semi-circular chamber within the manifold and opening outward, an inlet manifold having a vertical portion, laterally extending branch portions and an inwardly extending portion at the juncture of said vertical and branch portions, the latter portion registering with said chamber and connecting to said exhaust manifold, and a hollow oblong member rotatively connected within said inwardly extending portion adapted when arranged parallel to said exhaust manifold and branch portions of the inlet manifold to cut off communication between the latter and said chamber and when adjusted at right angles to such position to cut off direct communication between said vertical portions and branch portions of the intake manifold and to direct the mixture from the vertical portions into said chamber and thence outward into said branch portions.

In testimony whereof I affix my signature.
GEORGE R. WELCH.
